UNITED STATES PATENT OFFICE.

HUGH DIXON, SR., OF HARRISON, NEW JERSEY.

CARDING-MACHINE.

SPECIFICATION forming part of Letters Patent No. 451,920, dated May 12, 1891.

Application filed July 26, 1890. Serial No. 360,049. (No model.)

To all whom it may concern:

Be it known that I, HUGH DIXON, Sr., a citizen of the United States, residing at Harrison, in the county of Hudson and State of New Jersey, have invented certain new and useful Improvements in Carding-Machines; and I do declare the following to be a full, clear, and exact description of the invention, such as will enable others skilled in the art to 5 which it appertains to make and use the same, reference being had to the accompanying drawings, and to the letters of reference marked thereon, which form a part of this specification.

15 This invention relates to certain new and useful improvements in carding-machines, and has for its object to compress and render smooth the selvage-edge of the sliver or wadding and provide simple and efficient 20 means for carrying the invention into successful operation.

The improvement consists, essentially, of a guard which is located at the edges of the lap-belt, the guard being trough-shaped and 25 slightly flaring at the receiving end to permit the wadding to readily enter therein.

The improvement also consists of the novel features and the peculiar construction, arrangement, and combination of parts, which 30 will be hereinafter more fully described and claimed, which are shown in the accompanying drawings, in which—

Figure 1 is a side view of a carding-machine, showing the relative position of my improved guard. Fig. 2 is a central longitudinal section of the machine. Fig. 3 is a detail view of the invention.

To better illustrate the application of the invention and show its related position I have 40 shown a carding-machine in which A represents the frame, which is of suitable construction to support the operating parts of the machine. The conveyer a , composed of an endless band or apron a' and transverse 45 slats a^2 , is supported at its ends on the rollers a^3 and a^4 . The feed-rollers c and c' , one above the other, are arranged some distance from the inner or delivery end of the carrier

a . The table or feed-plate b , arranged between the delivery end of the carrier a and 50 the feed-rollers, receives the lap and guides it between the rollers c and c' . d and d' represent the licker-in.

The knives K , which remove the dirt and dust from the lap, are arranged at the receiving end of the licker-in d , and at a point just below the feed-rollers. E represents the doffer.

f is the combination for removing the sliver from the doffer. The belt for receiving 60 the sliver or wadding passes around the rollers g , and is interchangeable to adapt it to the required length of the sliver or wadding. The rollers l at the ends of the belt compress the wadding.

The guard Q beneath the licker-in and the doffer is continuous and catches the dust from the cotton. The belt L is interchangeable with longer, shorter, narrower, or wider belts, thereby regulating the size of the wad.

One of the standards, which forms a support for the belt L , as the standard N , is adjustable on the frame of the machine to and from the other standard N' , to adapt the position of the rollers g and g' to the length of 75 the belt L . The bolts N , which fasten the standard N' to the frame, pass through slots in the said frame, as shown in Fig. 2.

The guards F , one for each side of the machine, are secured to the standards N' and 80 embrace the edges of the belt L . These guards are trough-shaped, as shown in Fig. 3, and flare slightly at the receiving end, as shown at f in said Fig. 3. The edges of the lap pass through these guards and are condensed and rendered smooth and even.

The machine is operated in the usual way, and the lap as it leaves the doffer is received on the belt L and is carried by it between the guards F , which compress and 90 smooth the edges of the said lap.

Having thus described my invention, what I claim as new, and desire to secure by Letters Patent, is—

1. In a carding-machine, the combination, 95 with the lap-belt, of the trough-shaped

guards at the edges of said belt to condense the edges of the sliver, substantially as described.

2. In a carding-machine, the combination, 5 with the wad or sliver belt, of the trough-shaped guards embracing the edges of the said belt and made slightly flaring at the receiving end, substantially as shown, and for the purposes specified.

In testimony whereof I affix my signature in presence of two witnesses.

HUGH DIXON, SR.
